UNITED STATES PATENT OFFICE.

OLE L. LARSON, OF MINNEAPOLIS, MINNESOTA.

CORRUGATED ROTARY SIEVE.

1,139,041.

Specification of Letters Patent. Patented May 11, 1915.

Application filed September 5, 1914. Serial No. 860,457.

To all whom it may concern:

Be it known that I, OLE L. LARSON, a citizen of the United States, residing at Minneapolis, in the county of Hennepin and State 5 of Minnesota, have invented certain new and useful Improvements in Corrugated Rotary Sieves; and I do hereby declare the following to be a full, clear, and exact description of the invention, such as will enable others skilled in the art to which it 10 pertains to make and use the same.

My invention relates to rotary sieves, and is particularly directed to the provision of an improved cleaning device for corrugated 15 rotary sieves of the character disclosed and claimed in my pending application, Serial Number 819,959, filed February 20th, 1914, and entitled "Corrugated rotary sieve".

Generally stated, the invention consists of 20 the novel devices and combinations of devices hereinafter described and defined in the claims. In fact, a corrugated rotary sieve constructed from wire netting has been found highly efficient for the separation of 25 wheat and oats and various other materials, but there has been considerable difficulty in providing efficient sieve cleaning devices for rotary sieves of the above noted character. Oats frequently pass partly through the 30 meshes of such a sieve and become lodged or caught therein. Efficient separation requires that these oats and like objects be constantly forced out of the sieve meshes, so that the entire sieve surface is always oper- 35 ative.

I have found that a corrugated roller ar- 40 ranged to work against the outer corrugated surface of the sieve makes the most efficient kind of cleaning device.

The preferred form of the arrangement 45 above indicated is illustrated in the accom- 50 panying drawings, wherein like characters indicate like parts throughout the several views.

Referring to the drawings: Figure 1 is a 55 plan view of the improved sieve and clean- 60 ing device; Fig. 2 is a vertical section taken on the line $x^2 x^2$ on Fig. 1; and Fig. 3 is a transverse vertical section taken on the line $x^3 x^3$ on Fig. 1.

The numeral 1 indicates a suitable frame- 65 work having bearings 2 in which a shaft 3 is journaled. This shaft 3 carries spider- 70 like heads 4 which, in turn, carry the woven 75 wire sieve 5. The said sieve 5 has a general

cylindrical form, but is formed with longitudinally extended circumferentially spaced corrugations so closely positioned that the said corrugations run, one into the other. On one end of the shaft 3 is shown a pulley 60 6 over which a power driven belt, not shown, may be run to impart rotary motion to the sieve.

The numeral 7 indicates a corrugated cleaning roller, the corrugations of which 65 run in the corrugations of the sieve 5, much like a gear. This cleaning roller 7 is preferably also made from woven wire screen bent to form longitudinally extended circumferentially spaced corrugations. The 70 ends of the said roller forming sieve 7 are attached to heads 8 which are preferably provided with trunnions 9 loosely seated in the open seats 10 of bearing brackets 11 that are secured on the end portions of the frame 75 1, immediately above the ends of the corrugated sieve 5. The cleaning roller is thus gravity seated on the corrugated sieve in such manner that its corrugations will closely engage the corrugations of the sieve, 80 but the said cleaning roller will be free to rise and fall to adapt itself to all irregularities in the corrugated sieve. In this way, the best possible kind of a cleaning action is obtained and the cleaning roller, in addition 85 to its frictional contact with the corrugated surface of the sieve, will vibrate more or less and increase the sieve cleaning action by setting up a vibration therein, which vibration, furthermore, increases the separating 90 efficiency of the sieve.

It will, of course, be understood, that in the grain separating action, the grain will be fed into one end of the corrugated sieve 5 and will be fed out of the other end thereof, 95 and that, hence, in practice, the said sieve will usually be given an inclination in a direction from its receiving toward its delivery end.

The best arrangement of the cleaning 100 roller is substantially that illustrated in the drawings, but any kind of a corrugated ro- 105 tary cleaning roller or member, engageable with the corrugated sieve and rotating with a gear-like engagement in connection therewith, would be within the scope of my invention.

What I claim is:

1. The combination with a rotary longitudinally corrugated sieve, of a rotary cor- 110

rugged sieve cleaning device engaging the corrugated sieve and having a gear-like rotating contact therewith.

2. The combination with a rotary sieve 5 constructed from wire netting bent to form longitudinally extended circumferentially spaced corrugations, of a corrugated sieve cleaning roller also constructed from wire netting rotatably mounted for gear-like en-

gagement with the corrugations of said 10 sieve.

In testimony whereof I affix my signature in presence of two witnesses.

OLE L. LARSON.
